(57) CLAIM

The ornamental design for a handbag, as shown and described.

DESCRIPTION

FIG. 1 is a front elevational view of ornamental handbag in accordance with the new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a view of the horizontal striped surface of the handbag of FIGS. 1-6.

The straps are shown broken away to indicate indeterminate length.

A portion of the fabric from the handbag is shown enlarged for clarity of illustration.
